United States Patent Office.

MICHAEL KNAPP AND JOHN KNAPP, OF HUDSON CITY, NEW JERSEY.

Letters Patent No. 70,576, dated November 5, 1867.

IMPROVEMENT IN DOOR-LOCKS.

The Schedule referred to in these Letters Patent and making part of the same.

TO ALL WHOM IT MAY CONCERN:

Be it known that we, MICHAEL KNAPP and JOHN KNAPP, of Hudson City, in the county of Hudson, and State of New Jersey, have invented a new and improved Door-Lock; and we do hereby declare that the following is a full, clear, and exact description thereof, which will enable others skilled in the art to make and use the same, reference being had to the accompanying drawings, forming part of this specification, in which—

Figure 1 represents a side view of our improved lock, the front-plate being removed, and the bolt being unlocked.

Figure 2 is a similar view, showing the bolt in the locked position.

Figure 3 is a vertical cross-section of the same, the plane of section being indicated by the line *z z*, fig. 2.

Figure 4 is an end view of the key.

Similar letters of reference indicate like parts.

This invention relates to a door-lock, in which compound tumblers are used, the main tumbler being locked by an auxiliary tumbler whenever the door is locked, while, when unlocked, the bolt is perfectly free, and can be moved directly by the key. The parts are so arranged that the key can only be turned in one direction, both for locking and unlocking. By the application of the auxiliary tumbler the bolt is held firm when locked, and cannot be moved back by pressing from the outside, which is the case in most spring-bolt locks.

A represents the case of the lock B is the bolt, to the tail end of which a spiral spring, *a*, is secured, which has the tendency to draw the bolt in; C is a bar, which is arranged parallel with the bolt B, and which has two tumblers, *b b*, which project at right angles from its ends towards the bolt B. A spring, *c*, presses the ends of the tumblers *b b* against the bolt B. These tumblers *b* are guided between lugs *d d*, which are stationary, arranged in the case A, as shown. The key-hole is in the square or oblong space formed between the bolt B and the bar C. When the key is inserted through the key-hole, and turned in the direction of the arrow 1 in fig. 1, its end will (the bolt B being unlocked) strike against a lug or shoulder, *e*, formed on the bolt, and will move the same forward into the position shown in fig. 2. As soon as two recesses, *f f*, in the bolt B, come opposite to the ends of the tumblers *b b*, the latter will be thrown into these recesses by the spring *c*, and will thus lock the bolt B while the latter locks the door. For unlocking, the key is turned in the same direction as for locking, and comes in contact with the bar C, and throws it back against the spring *c*; thereby the tumblers *b* are withdrawn from the recesses *f* and the bolt B is again released, when the spring *a* will draw it in again, and the door will be unlocked. All these movements are very simple, and such a lock can be opened by any key, the bit of which is sufficiently long. To make it more difficult to open, one or more secondary tumblers D may be arranged above the bar C, in the manner shown. These secondary tumblers fit through a recess in the upper part of the tumblers *b* and guides *d*, as shown. The recesses in the latter are broader than that portion of the secondary tumbler that passes through them, so as to allow the motion of the arm C. That portion of the secondary tumbler which is in the tumblers B when the bolt B is unlocked, is broader than the other parts, as shown in figs. 1 and 2. A shoulder, *g*, is formed on each end of each secondary tumbler D, and a spring, *h*, has the tendency to draw the secondary tumblers towards the outer side of the lock. When the bolt B is unlocked, the secondary tumblers lie in the position shown in fig. 1, and cannot be moved longitudinally, as the broader parts in the tumblers *b* fit between the guides *d*. While the bolt is being locked, the secondary tumblers are carried towards the bolt B by the tumblers *b* until their broad portions come in line with the recesses in the guides *d*. The spring *h* then draws the secondary tumblers forward in the same direction in which the bolt is moved, so that their broad portions are drawn into the recess which is formed in the guides *d*. The shoulder *g*, at the tail end of the secondary tumbler, prevents the same from being drawn by the spring *h* further than is shown in fig. 2. The broad parts of the secondary tumblers will thus be in the recesses in *b* and *d* at the same time, as shown, and will thus completely lock the tumblers *b*, preventing them from being withdrawn from the bolt B. Not until the broad portions of the secondary tumblers are withdrawn from the recesses in *d* will the key have power to withdraw the tumblers *b* from the bolt B, and thereby unlock the latter. It will be seen that the motion to be imparted to the secondary tumblers by the key is at right angles to that of the tumblers *b*; and consequently the key must be so constructed that it will move the one in the direction of the arrow 2, and the other in that of the arrow 3. For this purpose we have provided the bit E of the key with lugs *j*, which project from its sides, as shown in fig. 4. These lugs fit into recesses or against shoulders in the secondary tumblers,

and draw the same in direction of the arrow 2. Then the key will be able to push the tumblers *b* out of the bolt *B*.

What we claim as new, and desire to secure by Letters Patent, is—

1. Guiding the secondary tumbler *D* through the slotted guides *d* and through the grooved tumblers *b b*, said secondary tumbler provided with the projections *g*, as described, and connected with the spring *h*, operating as and for the purpose specified.

2. The combination and arrangement of the bolt *B*, tumblers *b b*, secondary tumblers *D*, guides *d*, and springs *a c h*, all operating as described, for the purpose specified.

3. So constructing a lock that the same can only be locked and unlocked by turning the key in one direction only, as set forth.

MICHAEL KNAPP,
JOHN KNAPP.
